DESIGN FOR A DRIP COFFEEPOT OR ANALOGOUS ARTICLE

Chauncey E. Waltman, Chicago, Ill., assignor to Porcelier Manufacturing Company, Greensburg, Pa., a corporation of Pennsylvania

Application December 17, 1935, Serial No. 60,133

Term of patent 3½ years

To all whom it may concern:

Be it known that I, Chauncey E. Waltman, a citizen of the United States and a resident of Chicago, Cook County, Illinois, have invented a certain new, original, and ornamental Design for a Drip Coffeepot or Analogous Article, of which the following is a specification, reference being had to the accompanying drawing, forming a part thereof.

In the drawing:

In the drawing the dominant features of the design are shown in full lines.

I claim:

The ornamental design for a drip coffeepot or analogous article, as shown and described.

CHAUNCEY E. WALTMAN.
